UNITED STATES PATENT OFFICE

132,049

DESIGN FOR A WOVEN TEXTILE FABRIC

George A. Niedner, New York, N. Y.

Application March 10, 1942, Serial No. 106,136

Term of patent 3½ years

To all whom it may concern:

Be it known that I, George A. Niedner, a citizen of the United States of America, residing in New York city, county of New York, and State of New York, have invented a new, original, and ornamental Design for a Woven Textile Fabric, of which the following is a specification, reference being had to the accompanying drawing, forming part thereof.

The figure on the drawing is a plan view of a woven textile fabric showing my new design. The design unit is contained between the dot and dash lines, which unit is repeated in regular succession as indicated by the extensions beyond the unit boundaries.

I claim:

The ornamental design for a woven textile fabric, substantially as shown and described.

GEORGE A. NIEDNER.
